ANCHORAGE DEVICE

Application filed March 23, 1929. Serial No. 349,413.

This invention relates to improvements in anchorages, particularly of the type intended for securing or bonding a facing to a structural member, and it consists of the constructions, combinations, and arrangements herein described and claimed.

An object of the invention is to provide a simple and thoroughly efficient device for securely bonding or anchoring facing material such as brick, tile, stone, terra cotta and the like to reinforced concrete columns or walls or other structural parts of buildings.

Another object of the invention is to provide an anchorage which is to be embedded in a plastic or other structural member, and consists, essentially, of a slotted tubular structure into which the head of an anchor will be inserted upon presentation in one position then given a quarter-turn to assume the position that it will ultimately retain.

Other objects and advantages will appear in the following specification, reference being had to the accompanying drawings, in which:

25 Figure 1 is a cross section of a portion of a concrete column or other structural member, illustrating the application of a number of the anchorages and anchors used therewith, the bricks that are bonded by the latter being shown in plan,

Figure 2 is an enlarged view of one of the anchorages and anchors,

Figure 3 is a section taken substantially on the line 3—3 of Figure 2,

35 Figure 4 is a sectional view illustrating a slightly modified form of the anchorage, this being particularly adaptable as a pipe hanger,

40 Figure 5 is a side elevation of the modified anchorage, a portion being broken out and certain end-closures being illustrated,

Figure 6 is an end elevation of the anchorage in Figure 5, particularly illustrating one of the end-closures.

45 Many plans have been devised and executed for securing an outer facing or veneer such as brick and the like, to an internal structural member such as a concrete or other column, but apparently the advantages of a simple bonding device are yet to be realized

for, although such devices are in use, yet in many instances they are far from being simple either from the standpoint of actual structure or installation.

Reference is made to the drawings. An 55 internal structural member 1, which in this instance is regarded as a reinforced concrete column or wall, has a number of bonding devices 2 incorporated therein, these being herein identified as anchorages. Since the construction of each bonding device is alike, the description of one will suffice for all.

The anchorage 2 in Figures 1, 2 and 3 comprises a tubular structure that is set vertically in the member 1 and defines a continuous, 60 vertical channel which may, if desired, run full length of said member. It is a matter of judgment with the mechanic whether the anchorage shall run full length as just stated. The anchorage may be cut to size in the shop, 70 or it may be separated into desired lengths on the job. In any instance it is intended to be installed in the wall in order that the anchor 3 may be inserted and locked in position as the facing 4 is erected. 75

Inwardly curled portions 5 of the anchorage 2 define a slot 6 and depressions 7. The slot constitutes the entrance to the anchorage, and as shown in Figure 2 is narrower than the cross sectional diameter of 80 the tubular part of the anchorage. The portions 5 terminate in flanges 8. It is behind these and into the depressions 7 that the concrete is filled in the pouring of the member 1, these fillings ultimately defining 85 lugs which contribute in a large measure to retaining the anchorage in absolute immovability.

The primary purpose of the flanges 8 is to provide places where the anchorage can be 90 secured to the form boards. Nails will be lightly driven through the flanges and into the boards from the inside of the form. The boards are later removed without difficulty and without disturbing the anchorage. 95

A head 9 on the inner end of the anchor 3 will occupy the position in the anchorage 2 shown in Figure 2. The insertion of the head 100 is made by presenting it edge-on to the slot 6 and giving it a quarter-turn so that it assumes

the position already mentioned. The outer end of the anchor terminates in a ring 10 or other configuration, the purpose of which is to increase the bonding effect when the mortar is spread over the anchor during the erection of the facing 4.

Figures 4, 5 and 6 illustrate a modification of the anchorage that is particularly adaptable as a pipe hanger. Those parts of this anchorage which are similar to the first form are identified by corresponding reference numerals without necessarily repeating the specific description. It is observed that the modified anchorage has an upstanding fin 11. This fin is perforated at 12 so that the plastic material of the member 1 may enter and increase the bond.

It is optional whether the fin 11 shall comprise a single member integral with a single tubular structure 2, or whether the latter shall be medially separated to compose half-sections and each section provided with a flange to compose the fin 11 when the sections are assembled as in Figure 4. In either case the fin 11 and its perforations 12 will increase the carrying capacity of the anchorage, well adapting the latter to the purposes of a hanger.

The anchor 3, although similar to that shown in Figures 1 and 2, may be replaced by any device that will serve the purpose of a hanger. The anchorage 2 in Figures 4 and 5 will be cut off in relatively short lengths, these being such as the mechanic may judge necessary to allow him space for adjusting the hanger to the right line. The head 9 of the hanger 3 is presented to the slot 6 as before, then given a quarter-turn so that it will remain locked in the pendant position.

End-closures 13 prevent filling the modified anchorage 2 with the plastic material of the ceiling or other structural member 1 and also prevent the collapse of the half-sections upon each other while assembling the tubular structure. These comprise cups 14 which are inserted in the ends of the anchorage. Each has a rim or flange 15 which extends beyond the sides of the cup thus completely closing the end of the anchorage. The flanges abut the edges of the tubular structure and limit the insertion of the end-closures. The flanges have extensions 16 that fit over the ends of the slot 6 for the purpose already stated.

It is understood that the end-closures 13 must remain in place when the modified anchorage is once installed in the member 1. The anchorage 2, while usually used in short lengths when serving as a pipe hanger, will be provided long enough to afford sufficient latitude for the adjustment of the anchor 3.

It will require but a brief review to emphasize the mode of use of the bonding device in Figures 1 and 2. The anchorages 2 will extend vertically of the structural member 1,

and define slots or channels that will usually be continuous. As the outer facing 4 is erected, the anchors 3 will be inserted in the slots 6 and anchorages 2 in the manner already brought out, and imbedded in the mortar which is spread upon the various layers of bricks or the like. Some of the mortar will be pressed into the anchorages to surround the heads 9 and thus increase the bond.

While the construction and arrangement of the anchorage device herein described and claimed is that of a generally preferred form, obviously modifications and changes may be made without departing from the spirit of the invention or the scope of the claims.

I claim:

1. An anchorage comprising a tubular structure having an entrance slot, and end-closures for the ends of said structure comprising cups fitted into the tubular structure, and flanges on the cups to abut the edges of said structure to limit the insertion of the cups extending beyond the sides of the cups and including extensions covering the ends of the slot.

2. An anchorage comprising separably assembled half-sections having flanges, corresponding flanges having perforations and being abuttable to compose a fin and convert the half-sections into a tubular structure, and end closures fitting in said tubular structure to hold the perforations in matching relationship and to prevent relative sliding and the collapse of the half-sections upon each other.

3. An anchorage comprising a tubular structure having an entrance slot, end-closures for the ends of said structure, comprising cups fitted into the tubular structure, flanges on the cups extending beyond the sides of the cups to abut the edges of said structure to limit the insertion of the cups and including extensions covering the ends of the slot, and an anchor having a head insertible in the entrance slot and substantially matching the inside cross sectional contour of the structure when in the suspended position.

4. An anchorage to be embedded in a support, said anchorage comprising a tubular structure which is substantially circular in cross section and having a slot narrower than the cross-sectional dimension, and an anchor having a head to occupy the tubular structure crosswise, and a shank extending from the head out of the slot, said shank being of less thickness than the width of the slot to enable lateral adjustments of the shank in the event of misalignment of the anchorage in its support, said head being substantially circular to enable turning when making said adjustments.
